IRONING TABLE

Harvey E. Hortman, Jr., Southampton, Pa., assignor to Proctor Electric Company, Philadelphia, Pa., a corporation of Pennsylvania

Application December 19, 1950, Serial No. 201,623

4 Claims. (Cl. 38—123)

1

This invention relates to adjustable and collapsible ironing tables and more particularly to the type employing pivotally-interconnected crossed legs.

A main object of this invention is to provide a novel height adjustment mechanism.

Another principal object of the invention is to provide an improved ironing table of this type which may be adjusted to various heights but will not completely collapse during use, and which may be completely collapsed merely by tilting the table upward from its normal position of use while collapsing the legs toward the table top.

A more specific object of the invention is to provide such an ironing table wherein one of the supporting legs is connected to the table top by a fixed pivot connection while the other supporting leg is connected to the top by a sliding pivot connection, enabling different height adjustments and complete collapse of the table, and wherein a gravity-operable stop means is provided to prevent complete collapse of the ironing table when it is set up for use, said stop means permitting collapse of the table when caused to gravitate to an inoperative position.

Other objects and features will be apparent from the accompanying disclosure.

The invention may be fully understood from the following detailed description with reference to the accompanying drawings, wherein

Fig. 1 is a side elevational view, on relatively small scale, of the ironing table set up for use;

Fig. 2 is a fragmentary bottom view showing the adjusting mechanism;

Fig. 3 is a sectional view taken along line 3—3 of Fig. 2;

Fig. 4 is a transverse sectional view taken along line 4—4 of Fig. 3;

Fig. 5 is a sectional view similar to Fig. 3, showing the manner in which complete collapse of the ironing table is prevented during use;

Fig. 6 is a sectional view taken along line 6—6 of Fig. 3;

Figs. 7 and 8 are detail views showing the action which takes place during collapse of the ironing table; and

Fig. 9 is a side elevational view of an ironing table in the completely collapsed condition.

Referring first to Fig. 1, the ironing table comprises a top 10 and crossed legs 11 and 12 pivotally interconnected at 13. Preferably the leg 11 comprises a single elongate member with a transverse foot 14, while the leg 12 comprises a pair of parallel elongate members between which the leg 11 extends and which are provided with a 55 leg 12. When the pin 18 is seated in any one of

2

transverse foot 15. The ironing table is preferably of all metal construction, and the supporting legs and their transverse feet are preferably of tubular form.

5 The upper end of leg 11 is connected to the table top 10 by means of a fixed pivot connection comprising a transverse pin 16 fastened to said leg, for example by being welded thereto, and bearing brackets 17 depending from the table top and rotatably supporting the pin 16. The upper end of leg 12 is connected to the table top 10 by means of a sliding pivot connection comprising a transverse pin 18 secured to said leg, and a slotted retaining guide 19 secured to the table top and along which the pin 18 is slidable.

Referring now to Figs. 2 to 6, while the present invention is not concerned with the specific structure of the table top 10, the construction thereof may be as shown, comprising a flat surface plate 20 secured to a supporting and rigidifying member 21 shaped in cross section as clearly shown in Figs. 4 and 6. The table top is preferably provided with a plurality of transverse brace members, two of which are shown at 22 and 23, these 25 serving to support the slotted retaining guide 19.

As shown in Figs. 3 and 5, the retaining guide 19 is provided at its end portions with cam slots 24 and 25 through which extend fixed transverse pins 26 and 27 which are carried respectively by 30 the transverse brace members 22 and 23. The latter members are formed to provide channel portions 28 and 29 within which the pins set. By virtue of the slots 24 and 25, the retaining guide 19 is movable to a limited extent downward and toward the left, as viewed in Figs. 3 and 5, but it is retained in its normal position by a helical tension spring 30 having one end secured to the retaining guide 19 at 31 and having its other end secured to a lug 32 depending from the underside of the table top. The retaining guide 19 is prevented from side sway, being constrained to the abovementioned slight movement in a vertical plane by means of inverted U-shaped guides 33 and 34 which are apertured to accommodate the pins 26 and 27. Cam slots 24 and 25 are identical and comprise upper portions 24a and 25a, respectively, of approximately 45° slope and lower portions 24b and 25b, respectively, of rather low slope of approximately 18°, the purpose of which will be described hereinafter.

Adjacent to the retaining guide 19, there is provided a stationary rack member 35 fixedly secured to the table top and having recesses or notches 36 to receive the sliding pivot pin 18 of leg 12. When the pin 18 is seated in any one of

the recesses 36, the ironing table is adjusted to a particular height. Whenever it is desired to change the adjustment, the retaining guide 19 is moved downwardly by means of a manually operable member 37. The latter is in the form of a transverse pin disposed in a channel portion 38 of the transverse brace member 22, and having an outwardly extending handle portion 39 and an inner crank portion 40. The crank portion engages a recess 41 in the retaining guide 19. Rotation of the crank member 37 through its handle portion 39 causes movement of the retaining guide 19 downward and to the left against the action of its spring 30, thus causing removal of pin 18 from the rack member 35 and permitting the pin 18 to slide in the slot 19a. Release of the crank member 37 causes return of the retaining guide 19 to its normal position by the spring 30, thus causing pin 18 to seat in a different recess of the rack member 35 to maintain the new adjustment.

As shown in Figs. 2 and 3 slide ways 46 and 47 are formed as raised area on two of the ribs of the rigidifying member 21 to provide bearing surface for pin 18 during sliding movement thereof. Adjacent the ends of these slide ways 46 and 47 are formed detent buttons 48 and 49 which serve to hold the legs in their collapsed position as shown in Fig. 8. The detent buttons require that a finite amount of work be done in extending spring 30 to set the table into its operative position. The table can be set up by either: (a) manipulating the manual member 37 thus forcing the sliding pivot pin 18 down so that it can freely pass the detent button, or (b) exerting a force between leg 11 and the table top 10 to move guide 19 down against the action of spring 30 and over buttons 48 and 49 onto the slide ways 46 and 47. The mechanical advantage offered by the leg necessitates only a moderate amount of force to have the sliding pivot pin 18 move the guide 19 to free itself of the detent. From the slide ways pin 19 travels down a ramp 50 and into one of the notches 36 depending on where the particular setting up motion is stopped.

During adjustment of the ironing table toward its lowermost height, the pin 18 moves in the direction away from the fixed pivot pin 16 (Fig. 1) or toward the left, as viewed in Fig. 5, and were it not for the feature now to be described, there would be danger of unintentional complete collapse of the ironing table during adjustment thereof if the pin 18 happened to move beyond the recesses of the rack member 34. To prevent this, there is provided a gravity stop member 51 pivotally connected at 52 to the end portion of the rack member 35 and adapted to gravitate against a stop surface 50a formed on the ramp member 50. As may be seen in Fig. 5, this stop member prevents the pin 18 from moving beyond a predetermined point, thus preventing complete collapse of the table.

When it is desired to collapse the table, the retaining guide 19 is moved to permit freedom of pin 18, as above described, and the table is tilted upwardly from its position of use, permitting the gravity stop member 51 to gravitate to an inoperative position as shown in Fig. 7. Then, the pin 18 is free to move in slot 19a sufficiently to permit complete collapse of the table. Fig. 8 shows the pin 18 in the position to which it moves to effect complete collapse of the table, while Fig. 9 shows the ironing table completely collapsed in a generally vertical position.

As may be clearly seen in Figs. 5 and 7, the slot 19a is formed to provide an offset 55 thus dividing the slot into a right-hand portion 56 disposed below the notches 36 and a left-hand portion 57 disposed slightly above the plane of the right-hand portion. It will be noted that when pin 18 bears against slide ways 46 and 47 that guide 19 is positioned through section 57 of slot 19a so that pins 26 and 27 are in the upper high slope portions 24a and 25a of the cam slots 24 and 25 and also that said pins are in the high slope portions during adjustment of the legs as in Fig. 5. Further these pins are in the low slope portions 24b and 25b when the table is in its operative position as shown in Fig. 3. The purpose of the cam slot configuration and offset in guide 19 is to permit free movement of the sliding pivot pin when desired. When moving the pivot pin 18 to or from its fully retracted or detent position and when moving from one operative height to another (one notch to another) the guide bar can move freely in the areas 24a and 25a of the cam slots and the sliding pivot pin is therefore unrestrained. The low slope areas 24b and 25b of the cam slots cooperating with pins 26 and 27 when the pivot pin is seated in one of the notched positions will not permit the weight of the legs acting through the sliding hinge pin to lower the guide 19. Thus merely lifting the table top will not allow the legs to move out of the particular notched position into some other operative height.

From the above description, it will be seen that the invention provides novel collapse-preventing means in an adjustable ironing table, which means is automatically rendered operative when the table is set up for use and is rendered inoperative when the table is tilted upwardly toward a vertical position. Moreover, it will be seen that the device is of simple construction and may be easily manufactured at relatively low cost.

While a preferred embodiment of the invention has been illustrated and described, it will be understood that the invention is not limited thereto but contemplates such modifications and other embodiments as may occur to those skilled in the art.

I claim:

- 50 1. In an adjustable and collapsible ironing table, a table top, a pair of pivotally interconnected crossed legs providing an adjustable and collapsible support structure for said top, a fixed pivot connection between said top and the upper end of one of said legs, a sliding pivot connection between said top and the upper end of the other leg, manually controllable latch means for retaining the sliding pivot in different positions to provide different height adjustments of the table, and means for limiting the movement of the sliding pivot in the direction away from said fixed pivot to prevent collapse of the table while in use, said limiting means comprising a gravity-actuated stop member which gravitates to an operative position in the path of movement of said sliding pivot when the table is set up for use and which gravitates to an inoperative position out of the path of movement of said sliding pivot when the table is tilted upwardly.
- 55 2. In an adjustable and collapsible ironing table, a table top, a pair of pivotally interconnected crossed legs providing an adjustable and collapsible support structure for said top, a fixed transverse pivot pin connection between said top and the upper end of one of said legs, a trans-

verse pivot pin connected to the upper end of the other leg, retaining guide means on said top slidably supporting the last-mentioned pivot pin, manually controllable latch means for retaining the sliding pivot pin in different positions to provide different height adjustments of the table, and means for limiting the movement of the sliding pivot pin in the direction away from said fixed pivot pin to prevent collapse of the table while in use, said limiting means comprising a 10 gravity-actuated stop member which gravitates to an operative position in the path of movement of said sliding pivot when the table is set up for use and which gravitates to an inoperative position out of the path of movement of said sliding pivot when the table is tilted upwardly.

3. An ironing table according to claim 2, wherein said table top is provided with transverse braces, and said guide means extends between two of said braces and is secured thereto. 20

4. In an adjustable and collapsible ironing table, a table top, a pair of pivotally interconnected crossed legs providing an adjustable and collapsible support structure for said top, a fixed 25 pivot connection between said top and the upper

end of one of said legs, a sliding pivot connection between said top and the upper end of the other leg, manually controllable latch means for retaining the sliding pivot in different positions to provide different height adjustments of the table, and means between said top and said other leg and in the path of movement of the sliding pivot for limiting the movement of the sliding pivot in the direction away from said fixed pivot to prevent collapse of the table while in use, said limiting means comprising a stop member and means mounting said stop member for gravitational movement to an operative position in the path of movement of said sliding pivot when the table is set up for use, said stop member being movable to an inoperative position out of the path of movement of said sliding pivot.
